THREAD CONTROLLING MECHANISM FOR SEWING MACHINES

Filed Dec. 14, 1927

FIG. 1.

FIG. 2.

FIG. 3.

FIG. 4.

UNITED STATES PATENT OFFICE

WALTER M. HANNEMAN, OF CHICAGO, ILLINOIS, ASSIGNOR TO UNION SPECIAL MACHINE COMPANY, OF CHICAGO, ILLINOIS, A CORPORATION OF ILLINOIS

THREAD-CONTROLLING MECHANISM FOR SEWING MACHINES

Application filed December 14, 1927. Serial No. 240,005.

The invention relates to new and useful improvements in a thread controlling mechanism for sewing machines, and more particularly to a mechanism for clamping the thread at predetermined times to aid in the proper control thereof.

It is a very common expedient in sewing machines to provide nipper springs through which the thread passes from the supply on the way to an active thread controlling member, which nipper springs at predetermined times are closed by means of a rotating cam, so that the thread is clamped and held so that the taking up of the thread by the controlling mechanism will be properly directed to the stitch forming elements.

An object of the present invention is to provide a housing for the cam which controls the nipper springs, which housing prevents the thread, if broken, from being wound on to the shaft or nipper spring cam.

A further object of the invention is to provide a supporting bracket for the nipper springs, which also operates to hold the housing from rotating with the shaft.

These and other objects will in part be obvious and will in part be hereinafter more fully disclosed.

In the drawings which show by way of illustration one embodiment of the invention—

Figure 1 is a plan view of a portion of a sewing machine showing the invention applied thereto;

Fig. 2 is a sectional view on the line 2—2 of Fig. 1;

Fig. 3 is a perspective view of the housing for the nipper operating cam and the parts of the shaft adjacent the thread controlling cam, and

Fig. 4 is a perspective view of the supporting bracket for the nipper springs.

The invention is directed to a thread controlling mechanism for sewing machines. It is a common expedient to provide a rotating thread controller which engages the thread between the supply and the stitching elements for taking up the thread at certain times, and giving it up at other

times, so as to aid in the formation of the concatenated thread loops and the drawing of the loops to set the stitches. Associated with this rotating thread controlling cam are nipper springs through which the thread passes from the supply to the controlling element. A cam co-operates with these nipper springs and operates to close the springs at predetermined intervals. This cam works in timing with the thread controlling member, so that the nipper springs will be closed when the thread is drawn on by the rotating controlling element, and thus the pull on the thread is directed to the portions thereof at the stitching point. This controlling element is often located close to the nipper springs. The present invention is directed particularly to a housing which houses the portion of the shaft adjacent the rotating thread controlling element, and which also in part houses the cam which controls the nipper springs. The housing is held from rotation, and therefore, if the thread should break, the housing will prevent the thread from falling on to either the rotating shaft or rotating cam, so that it will be wound thereon.

Referring more in detail to the drawings, the invention is shown as applied to a sewing machine which includes a frame 1 in which is mounted a main shaft 2 which is rotated in any suitable way. Located on this main shaft 2 is a rotating thread controlling cam 3. This rotating cam, as shown, is provided with a cylindrical projecting flange, the free edge of which is cam-shaped. Associated with this rotating cam are thread guides 4 and 5. The thread guide 5 is located within the projecting flange of the thread controlling cam 3, while the thread guide 4 is located outside thereof. These thread guides are carried by a support 6. The thread controlling mechanism shown in detail forms no part of the present invention, but is shown, described and claimed in the application of Charles F. Rubel, filed July 23, 1927, Serial No. 207,963. The thread as it is led from the supply, passes through suitable tensions, and then between the two nipper springs 7 and 8. These nip-

per springs are rigidly attached to a supporting bracket 9 by means of a clamping screw 10. The bracket is secured to the frame of the machine by screws 11, 11. It is on this bracket that the support 6 for the thread guides is mounted. These nipper springs 7 and 8 are normally slightly separated so that the thread passing between the nipper springs will run freely. The under nipper spring 7 is raised by means of a cam 12 at certain predetermined intervals. This cam 12 lies directly beneath the nipper springs and is mounted on the main shaft 2. As the main shaft 2 rotates, the cam will lift the lower nipper spring so as to cause the thread to be clamped. This clamping of the thread is in proper timing with the active projecting portions of the controlling cam, so that when the thread is drawn upon by the projecting portions, the thread will be clamped, and instead of pulling thread from the supply, it will pull back on the thread at the stitching point and properly take all slack out of the thread to aid in the formation of the concatenated loops, and to aid in setting the stitches.

Mounted on the shaft 2 is a sleeve 13 which carries a housing 14. This housing 14 (see Fig. 2) includes a radially projecting disk portion 15, and a laterally projecting flange. This housing is cut away so as to form a recess 16. A pin 17 on the bracket 9 is adapted to engage a slot 18 in the housing 14, and this prevents the housing from rotating on the main shaft 2. The housing is supported on the shaft, but does not rotate. The cam for operating the nipper springs works through the recess 16. This housing substantially encloses the cam which operates the nipper springs at the sides thereof, and on the face of the cam adjacent the thread controlling cam. If the thread at any time should break, and the end thereof adjacent the thread controlling cam, or the nipper springs drop down, it will engage either the sleeve 13 or the housing 14, and this will prevent the thread from being wound on to the shaft or on to the cam which operates the nipper springs.

It is obvious that the thread controlling mechanism may be used with various forms of stitch forming mechanism, but it is particularly adapted for use in connection with a looper thread. It is obvious also that the shaping of the thread controlling cam may be greatly varied without departing from the spirit of the invention which is directed to the housing for the nipper operating cam and the shaft adjacent the thread controlling cam.

Having thus described the invention, what I claim as new and desire to secure by Letters Patent, is—

1. In a thread controlling mechanism, a

shaft, thread clamping devices, a cam mounted on said shaft and adapted to operate said thread clamping devices, a stationary sleeve mounted on the shaft, a housing carried by the sleeve and enclosing the sides of said cam, said housing being cut away so that said cam may project through the housing and operate said thread clamping devices.

2. In a thread controlling mechanism, the combination of a shaft, a rotating thread controlling cam mounted on the shaft, clamping devices for the thread disposed between said thread controlling cam and the thread supply, a rotating cam mounted on said shaft and adapted to operate the clamping devices, and a stationary housing adapted to enclose the sides and the face of the cam operating the clamping devices which is adjacent the thread controlling cam, said housing being cut away at the face thereof adjacent the clamping devices so as to permit the cam to engage and operate said devices.

3. In a thread controlling mechanism, the combination of a shaft, a rotating thread controlling cam mounted on the shaft, nipper springs for clamping the thread passing from the supply to the thread controlling cam, a cam on said shaft adapted to close the nipper springs, a sleeve on the shaft, a housing carried by the sleeve and enclosing the sides of the cam operating the nipper springs and the face thereof adjacent the thread controlling cam, said housing being cut away at the face thereof adjacent the nipper springs, so that the cam for the nipper springs may project through and engage said springs, and means for preventing said sleeve and housing from rotating with the shaft.

4. In a thread controlling mechanism, the combination of a shaft, a rotating thread controlling cam mounted on the shaft, thread guiding devices associated with said cam, a support for said devices, a bracket on which said support is mounted, nipper springs mounted on said bracket, a cam mounted on the shaft and adapted to close said nipper springs, a sleeve mounted on the shaft, a housing carried by the sleeve and enclosing the sides and the face of the cam operating the nipper springs which is adjacent the thread controlling cam, said housing being cut away adjacent the nipper springs to permit the cam to project through and engage the nipper springs, and a pin carried by the bracket and adapted to engage a slot in the housing for holding the housing and sleeve from rotating with the shaft.

In testimony whereof, I affix my signature.

WALTER M. HANNEMAN.
